UNITED STATES PATENT OFFICE.

LOUIS LELONG AND JOHN ROSCOE MILLWARD, OF NEWARK, NEW JERSEY.

CRUMB-COLLECTING DEVICE.

1,143,840.

Specification of Letters Patent. Patented June 22, 1915.

Application filed August 26, 1913. Serial No. 736,766.

To all whom it may concern:

Be it known that we, LOUIS LELONG and JOHN ROSCOE MILLWARD, citizens of the United States, residing at Newark, in the 5 county of Essex and State of New Jersey, have invented new and useful Improvements in Crumb-Collecting Devices, of which the following is a specification.

The present invention relates to a device 10 for the sweeping up or gathering of bread crumbs and the like from the table after dining and embodies special features of arrangement and construction whereby it is particularly adapted to be made up of silver 15 or other high grade metal as a part of the table service.

Desirable features of our improved device consist in a compact arrangement of the operating parts so as to occupy the minimum 20 of space and wherein the bearings are inclosed entirely within the casing; the arrangement whereby the collecting pan is pivotally supported upon the counter shaft in a manner permitting it to be swung back 25 within the casing and wherein its fulcrum is removed from a position where it would be liable to catch in the table cloth; a particular form and arrangement of collecting pan affording a rear support for the device 30 and a desirable catch therefor also contained wholly within the casing so as to preserve the desired unbroken exterior surface for the casing. These and other features 35 of our invention will be understood from the accompanying drawing wherein the reference characters of this description are applied to like parts in the several views.

In the drawing Figure 1 illustrates an embodiment of our invention partially in plan 40 and partially in horizontal section; Fig. 2 is a cross-sectional view thereof; Fig. 3 is a perspective view of the same and Fig. 4 is an enlarged partial cross-sectional view better to illustrate the detail of the collecting 45 pan arrangement.

In the figures, 1 indicates a suitable casing for the operating parts which may be of the design and substantially of the size shown and desirably is of silver or other 50 precious metal and to which is attached, preferably rigidly, the handle 2. In suitable bearings 4—4 and 5—5 preferably arranged entirely within the interior of the casing there are journaled the respective shafts 6 and 7. The forward shaft 6 is the driving shaft and has fixed thereon at its opposite

ends, but within the casing, the driving-wheels or rollers 9—9.

Journaled on the shaft 6, between the wheels 9, is the hub 10 of the rotary brush 11 of cylindrical form as shown. To rotate the brush there is provided a pinion 12 fixed to the inner surface of one of the drive-wheels, the left as here shown, to engage a pinion 13 fixed on the rearward or counter-shaft 7. On the opposite end of shaft 7 is secured a pinion 15 in mesh with the pinion 16 secured directly to the hub 10 of the brush. Thus the movement of the driving wheels 9, as when they are rolled upon the table surface, will be transmitted to the brush 11 whereby it is rotated. The rotation of the brush desirably is at an increased speed, for example double the speed of the wheels as here provided for by reason of the driving pinion 12 having twice the diameter of that of the pinion 13; pinions 15 and 16 being shown of the same size.

The rotation of the brush in the embodiment here disclosed will be in the direction 80 whereby the lower part thereof will move rearwardly so as to brush the crumbs into a collecting pan 20 arranged at that side. The pan as here provided preferably is of the form shown having at its ends upwardly extending ears 21—21 apertured and fitted to the counter-shaft 7 whereby the shaft forms the bearings for the pan upon which it swings in the manner best illustrated in Fig. 4. As there shown the pan is formed with a 90 lower flat surface affording a good sliding surface to rest upon the cloth and the pan in its operative position, shown in Fig. 2, forms the rear support for the device; the support at the front being upon the wheels 95 9—9.

The casing 1 at its front portion desirably is concentric with the brush and elevated from the cloth by the wheels at its lower front edge sufficient to give a good clearance 100 for the passage thereunder of the crumbs to be picked up. At its rear portion the casing preferably is formed concentric with the shaft 7, as likewise is the rear portion of the pan 20 which desirably is arranged to have a sliding fit within the casing 105 so as to permit of its being swung backwardly as shown in Fig. 4 to permit of emptying its contents when desired.

To retain the pan in lower operating position we have devised a simple and efficient yieldable catch desirably formed by slitting

the rear upper part of the pan 20 to form the integral flat spring portions 23 oppositely arranged as shown in Fig. 1 and provided each with an offset projecting lip 24 5 adapted by registering with the recess 25 formed in the casing interior to retain the pan in lower operative position. The compressible catch so formed is simple and effective, having no detachable parts and, 10 moreover, is adapted to operate totally within the casing so as to have no protruding parts and preserves the unbroken exterior surface of the casing, particularly desirable in an article of this type.

15 An inturned flange 20' may be provided at the front edge of the pan and the front edge as shown is desirably curved slightly upward to be immediately adjacent to the brush. The pan is conveniently forced back 20 to empty by catching hold of its front edge with the finger and pulling rearwardly to overcome the yielding spring 23.

The bearings 4 and 5 are desirably of the form best shown in Fig. 4 consisting of 25 rectangular blocks or inserts fitted to complementary recesses r formed in the casing interior and held in position by the securing screws 26 whereby the parts may easily be taken out for cleaning or in the event of 30 constructing the casing of thinner metal the recesses r may be omitted.

We have thus produced a device particularly adapted for the purpose intended, eliminating additional securing parts and 35 bearings for the collecting pan and wherein we have obtained a degree of compactness permitting it to be made up commercially as a high grade article of for instance silver or gold as a part of the table service, at the 40 same time possessing the required utility.

Having described our invention, we claim:

1. A crumb collecting device comprising a suitable casing, drive wheels suitably journaled, a rotary brush journaled concentric 15 with the drive wheels, a counter shaft arranged parallel to the brush, driving connections on the counter-shaft in engagement respectively with the drive wheels and the brush whereby the brush is rotated from the 20 drive wheels and a collecting pan pivotally

supported on the counter-shaft to afford a rear support for the device and adapted to be swung rearwardly within the case to empty its contents.

2. A crumb collecting device comprising 55 a suitable casing, drive wheels suitably journaled, a rotary brush journaled concentric with the drive wheels, connections from the wheels to the brush whereby the brush is rotated, a collecting pan suitably journaled to afford a rear support for the device and adapted to be swung upwardly within the casing to empty its contents, a yieldable catch operating between the pan and the casing for retaining the pan in its operative 60 position and a handle on the casing.

3. A crumb collecting device comprising a casing, a drive shaft journaled in the casing, driving wheels fixed on the drive shaft, a rotary brush journaled on the drive shaft, a 70 counter shaft suitably journaled parallel to the drive shaft, a pinion at one end of the drive shaft and rotatively connected thereto, a pinion on the counter shaft in mesh therewith, a pinion at the opposite side of 75 the counter shaft, a pinion secured to the brush in mesh with said opposite pinion and a collecting pan arranged to the rear of the brush and pivotally supported on the counter shaft.

4. A crumb collecting device comprising 80 a suitable casing, drive wheels suitably journaled, a rotary brush suitably journaled, a counter shaft arranged parallel to the brush, driving connections on the counter shaft in 85 engagement respectively with the drive wheels and the brush whereby the brush is rotated from the drive wheels and a collecting pan pivotally supported on the counter shaft to be swung rearwardly within the case to empty its contents.

In testimony whereof we have signed our names to this specification in the presence of two subscribing witnesses.

LOUIS LELONG.
JOHN ROSCOE MILLWARD.
